GARBAGE BAG SUPPORT AND STORAGE DEVICE

Harold J. Comeaux, 1448 Bonnabel Blvd.,
Metairie, La. 70005

Filed Sept. 7, 1973, Ser. No. 395,060

Term of patent 14 years

Int. Cl. D7—07

U.S. Cl. D7—193

FIG. 2

FIG.4

FIG. 1 is a front elevational view of a garbage bag support and storage device showing my new design;

FIG. 2 is a top plan view;

FIG. 3 is a perspective view of the device in open condition; and

FIG. 4 is a perspective view in closed condition.

I claim:

The ornamental design for a garbage bag support and storage device, as shown and described.
